UNITED STATES PATENT OFFICE.

FRANK M. BECKER, OF BETHLEHEM, PENNSYLVANIA.

SNOWPLOW.

Application filed May 18, 1927. Serial No. 192,398.

My present invention has reference to a snow cleaning machine which is motor propelled and operated, and which includes means for gathering the snow, delivering the same to a conveyor, regulating the feed of the conveyor, delivering the snow from the conveyor onto a triturator and delivering the water emanated by the triturator on to the forward or receiving end of the device to melt or soften the snow at such receiving end so that the same can be more readily gathered and again conveyed into and treated in the machine.

The invention will be fully and comprehensively understood from a consideration of the following detailed description when read in connection with the accompanying drawings which form part of the application, with the understanding, however, that the improvement is capable of extended application and is not confined to the exact showing of the drawings nor to the precise construction described and, therefore, such changes and modifications may be made therefrom as do not affect the spirit of the invention nor exceed the scope thereof as expressed in the appended claims.

In the drawings:

Figure 1 is a side elevation of a snow plow in accordance with this invention.

Figure 2 is a top plan view thereof.

Figure 3 is an approximately central vertical longitudinal sectional view therethrough.

Figure 4 is a sectional view approximately on the line 4—4 of Figure 3.

Figure 5 is a plan view of the scoop.

Figure 6 is a detail sectional view approximately on the line 6—6 of Figure 1.

In carrying out my invention I employ a wheeled frame. On the frame there is supported a cab 2 which is arranged directly above the drive wheels 4 of the improvement. The frame supports thereon a motor 5 which is preferably of the internal combustion type of engines and which is provided with the usual control means for imparting motion to the axle for the drive wheels, for reversing the travel of the machine and for otherwise regulating the speed of travel or disconnecting the drive shaft when the motor is in operation. As these features are common in all motors of this type a detailed description thereof will not be attempted, but the motor operates a shaft 6 which is arranged transversely to its drive shaft.

The rear end of the frame 1 is preferably

elevated and is provided with steps that lead to the cab or body 2. On the outer end of the hood portion 7 of the cab and motor there is fixedly secured a cylindrical casing 8. The casing 8 may be of any desired length and preferably is comparatively thick or otherwise corrugated longitudinally to form the same with equidistantly spaced inner concavities that provide pockets 9. The forward wheels of the frame support the casing adjacent to the outer end thereof, and the outer end of the casing is cut at a downward inclination, as clearly disclosed by the drawings. This inclined front of the casing 8 is formed with an outwardly directed flange that is contacted by and has riveted thereto an outstanding flange on the outwardly curved side members or wings 10 of the improvement.

The bottom of the casing, at its said outer and flanged end has hingedly supported thereon, as at 11, the scoop of the improvement. As disclosed especially by Figure 5 of the drawings, the scoop is made up of any desired number of sections 12 and the outer edge of these sections have secured thereto equidistantly spaced upwardly curved fingers 13. Fixed on the straight portions of the fingers that connect the same with the respective sections of the scoop 12 there are bearing lugs 14 that contact with the ground surface. The end members of the scoop have their outer edges shaped to conform to the shape of the wings 10.

If desired the outer and open end of the cylinder 8 may have a spider arranged therein, but in any event there is arranged centrally and longitudinally in the cylinder a shaft 15. This shaft is journaled through a bearing opening in a spider 16 in the cylinder and is likewise journaled through a bearing opening in the rear wall 17 of the cylindrical body 8. The inner end of the shaft has fixed thereon a gear 18 that is in mesh with a pinion 19 journaled on a transverse shaft 20. Fixed on the shaft 20 there is a sprocket wheel over which is trained an endless chain 21 that is likewise trained over a sprocket wheel 22 that is fixed on the shaft 6. Freely mounted on the shaft 15 disposed directly opposite the inner wall 17 of the body 8 there is the hub 23 of a cone-shaped member 23' whose outer face is corrugated and which face is disposed opposite longitudinal ribs or enlargements 24 in the said body 8. The member 23' and its ribs 24 comprise the triturator

and the said triturator is held stationary in the casing 8. The member 23' is of metal and the ribs or enlargements 24 thereon are preferably of emery. Forward of the bearing 5 spider 16 there is fixed on the shaft 15 a screw conveyor 25. The conveyor terminates at the outer end or at the inlet mouth of the cylindrical body 8.

The top of the body 8, at the outer inlet 10 end thereof is formed with a notch or opening 26, and in a line with the longitudinal walls provided by said opening the said body is provided with upstanding ears 27. Journalled 15 between these ears there is a shaft 28. Free- ly revoluble on the shaft 28 there is a head member 29. The head member 29 is peripher- ally formed with oppositely arranged equi- distantly spaced outstanding ears 30. Three 20 pair of such ears are preferably provided, and the ears gradually decrease in width from their connection with the heads to the outer end thereof. Pivoted, as at 31, be- 25 tween each pair of ears 30 there are feeder blades 32. These blades are shaped to be received between the ribs of the spider con- 30veyor 25, and when the conveyor is revolved the blades will be successively brought be- 35tween the outer pairs of ribs of the said con- 35veyor. The blades provide means for feed- 40ing the snow between the ribs of the conveyor and in a like manner the pockets 9 provide means for preventing the rapid travel of the snow through the ribs of the conveyor onto the triturator 23.

The chamber in the cylindrical body 8, be- 35tween the spider 16 and the wall 17 is de- 40signed for the reception of water which emanates from the triturator, and this water is conveyed to a chamber 33 on whose lower 45wall there is secured a casing 34 for inter- meshing gears 35 and 36 respectively. The gear 35 has a shaft 39 provided with a pinion that is in mesh with a second pinion on a transverse shaft 40. The shaft 40 is jour- 50naled on suitable bracket bearings 41 on the inner or rear face of the plate 17. The shaft 40 has fixed thereon a sprocket wheel around which there is trained an endless sprocket chain 42 which is also trained around a sprocket wheel 43 on the motor driven 55shaft 6.

The shaft for the gear 36 operates a rotary 60pump and leading from the casing 33 for delivering water therefrom, when the pump is actuated, there are oppositely directed up- 55wardly and rearwardly inclined pipes 45, the outlet ends of which being rounded and being disposed at the sides of the outer and inlet end of the cylindrical body or casing 8. The 60pump is of the ordinary construction and is such as is commonly employed in automobiles for pumping oil. The pump comprises two intermeshing toothed wheels 35 and 36 respectively. The toothed wheel 35 of the pump is fixed on a shaft 39 that carries a

pinion which is in mesh with a second pinion on the transverse shaft 40.

The operation of the improvement may be briefly described as follows: When the motor is operated the machine will be propelled in 70 a forward direction. In this connection it might be well to state that suitable guide mechanism is provided for the front wheels of the device and operated by the usual steering mechanism in the cab 2. The sectional 75scoop will plow into the snow and direct the same upwardly into the cylindrical casing or housing 8 when the same is engaged by the conveyor 25 and delivered thereby onto the triturator 23'. The blades 32 will feed the 80 snow between the ribs of the conveyor, while parts of the snow will be received in the pockets 9 to prevent the snow from traveling too rapidly between the ribs of the conveyor. The rear end or rib of the conveyor compresses 85 the snow against the ribbed and corrugated triturator 23', and this snow is also acted on by the ribs 24 in the rear chamber of the body 8. The water emanated from the triturated snow will be delivered through 90 a passage 44 between the triturator and the conveyor into the chamber 33 and will be acted on by the pump therein so that such water is forcibly ejected through the pipes 45 onto the banks of snow in the front of the ma- 95chine. In this manner it will be noted that practically all of the snow received in the machine is reduced to a fluid state and as the same is forcibly ejected through the pipes 45 onto the street or path at the forward end of the 100 machine will not only have the snow removed therefrom but will be effectively washed and cleaned.

Having described the invention, I claim:—

1. A snow cleaning apparatus comprising 105 a wheel supported cylindrical casing, a spiral conveyor in the casing, a conical fixed triturator at the rear of the conveyor, said casing having a chamber below the triturator, a rotary pump in the chamber, pipes leading 110 from the pump to the forward end of the casing and means for simultaneously propelling the casing, and operating the conveyor and pump.

2. A snow cleaning apparatus comprising 115 a wheel supported cylindrical casing that has spaced longitudinal grooves forming pockets, a spiral conveyor in the casing, a conical fixed triturator in the casing at the rear of the conveyor, said casing having a chamber below 120 the triturator, a rotary pump in the chamber, pipes leading from the chamber to the forward end of the casing and means for simultaneously propelling the casing and for operating the conveyor and pump.

3. A snow cleaning apparatus comprising a wheel supported cylindrical casing, which is provided with equidistantly spaced grooves forming inner pockets, a spiral conveyor in the casing, a revoluble head, pivotally sup- 125

- ported feeder blades thereon movable between the spirals of the conveyor, a fixed triturator at the rear of the conveyor, said casing having a chamber below the triturator, a rotary pump 5 in the chamber, pipes leading from the chamber to the forward end of the casing, and means for simultaneously propelling the casing and operating the conveyor and pump.
4. A snow cleaning apparatus comprising 10 a wheeled motor driven cylindrical casing and a pivotally supported sectional scoop on the lower and outer end of the casing, outwardly curved ribs on the sides of the casing at the said ends thereof, a spiral conveyor in the casing and having its outer end disposed over the scoop, pivotally supported revolvably mounted feeder blades on the scoop designed upon the rotation of the conveyor to be successively received between the outer ribs of the conveyor, 15 20 25
5. A snow cleaning apparatus comprising a ribbed frusto conical triturator fixed in the casing in the rear of the conveyor, said conveyor having a chamber below the triturator, a rotary pump in the chamber, pipes leading from the chamber to the front end of the casing, and means actuated by the motor for the conveyor for simultaneously imparting rotary motions to the conveyor and the pump.
6. A snow cleaning apparatus comprising a motor propelled wheeled frame having a
- cylindrical casing supported thereon and 30 the rear wall of the casing being curved, the outer end of the casing being cut at an inward angle, side wings secured to the sides at the said end of the casing, a scoop pivoted on the lower wall at the said end of the casing and 35 comprising a plurality of sections, each having upwardly rounded fingers extending from the lower end thereof and having a lug on its under face at the juncture of the scoop with the fingers, a spiral conveyor in the casing, a feeder mechanism including blades disposed between the outer ribs of the conveyor and designed to be simultaneously brought between and out of such ribs when the conveyor is revolved, a triturator fixed 40 in the casing at the rear of the conveyor, said casing having a ribbed compartment between the triturator and the conveyor, and said casing having a chamber on the lower wall thereof disposed below the triturator and communicating with said compartment, a rotary pump in the chamber, pipes leading from the chamber to the front end of the casing, and means for simultaneously propelling the casing and operating the conveyor and pump. 45 50 55

In testimony whereof I affix my signature.

FRANK M. BECKER.
